UNITED STATES PATENT OFFICE.

JAMES F. REDDY, OF ROCHESTER, NEW YORK.

LIQUID-RAISING APPARATUS.

1,073,630.

Specification of Letters Patent. Patented Sept. 23, 1913.

Application filed November 25, 1907. Serial No. 403,580.

To all whom it may concern:

Be it known that I, JAMES F. REDDY, of Rochester, in the county of Monroe and State of New York, have invented certain new and useful Improvements in Liquid-Raising Apparatus; and I do hereby declare the following to be a full, clear, and exact description of the same, reference being had to the accompanying drawings, forming a part of this specification, and to the reference-numerals marked thereon.

The present invention which relates to liquid raising apparatus of the type in which compressed air is employed as the elevating medium, has for an object to provide a construction by which a strong, regulatable flow of liquid may be obtained from driven wells.

Another object is to provide for the cleaning of the apparatus by agitating the body of liquid to be raised.

To these and other ends the invention consists in certain improvements and combinations of parts all as will be hereinafter more fully described, the novel features being pointed out in the claims at the end of the specification.

In the drawings wherein I have shown one embodiment of my invention: Figure 1 represents a view in side elevation: Fig. 2 a sectional view of the upper portion of the same: Fig. 3 a sectional view of lower portions: Figs. 4, 5 and 6 each represent sections on line *a*—*a* and line *b*—*b* of Fig. 2, and show the three positions of both valves; and Fig. 7 represents a detail view of the upper portion of the apparatus illustrating the connection with the air supply.

One of the features of this invention is the provision in the air supply pipe of one or more adjustable nozzles, by which the discharge of the air can be regulated and in this manner the flow varied, and another feature is the provision of means for connecting the air supply to the discharge tube and to the well casing whereby a surging of the liquid to be elevated may be effected, this causing the cleansing of the apparatus.

A well casing 1 of any suitable form is driven in the usual manner through the earth to a stratum of stone or other hard substance which does not require to be supported against caving in; and arranged within the well casing and extending below the same is the liquid discharge tube 2 preferably having a perforated base or strainer

3 at its lower end secured thereto by screw threads or other means.

Connected to the upper end of the well casing and of the discharge tube is a head which is divided into two chambers 4 and 5, the chambers being formed by contracting the head at 6 and the chamber 4 having a discharge 7. Suitable means, such as screw threads 8 at its lower end, serve to secure the well casing to the head: while suitable means such as screw threads 9 on the inner wall at the reduced or contracted portion serve to secure the discharge tube and permit the latter to communicate with discharge 7.

The perforated base or strainer may be cleansed by means of devices for effecting a surging of the liquid within the casing. These devices consist in the present instance, of two connections 10 and 11, leading from an air supply 12 and having valves 13 and 14 arranged therein. These valves are of the two-way rotary type, that is, in addition to the usual inlet and discharge they have a discharge 15 leading to the atmosphere. The plug of the upper valve has one port 16 while that of the lower valve has ports 16^a and 16^b. The relation of the valves to each other is fixed and is such that when the well casing communicates with the atmosphere the discharge tube communicates with the air supply and vice versa, and when one is entirely closed the other will be entirely closed. For instance as shown in Fig. 4 when the port 16^a in the valve 14 communicates with the air supply the port of valve 13 will connect the discharge with the atmosphere, when the port of valve 13 communicates with the air supply, as shown in Fig. 5, the port 16^b of valve 14 will cause the well casing to communicate with the atmosphere; and when both valves are entirely closed they will occupy the positions shown in Fig. 6. It is preferred to mount one valve directly above the other and have their operating portions 17 directed toward each other so that a rotary shaft 18 may connect them, sockets 19 being formed in the ends of the shaft to receive the operating portions 17; but, of course, any other suitable means may be employed for simultaneously operating the valves to alternately connect the casing and the tube with the supply pipe.

The raising or elevation of the liquid is

secured by a suitable device which in this instance comprises an air pipe connected at its upper end by a flexible pipe 100 to the air supply 12, resting at its lower end on the bottom of the strainer, and vertically adjustable at its upper portion in order to vary the discharge from one or more nozzles arranged one above the other therein, the valves being preferably constructed in a manner to be described.

10 A suitable means for effecting the vertical adjustment of the air pipe comprises a rotatable member 20 in the form of a nut having a hand wheel by which it is operated. This nut engages screw threads 21 on the air pipe and is secured to the bushing 22 by screws 23 which engage in an annular groove in the bushing, the latter serving to hold packing about the air pipe to prevent 15 the escape of air or liquid. A nut 30^a locks the rotatable member against movement.

20 The air pipe comprises preferably a plurality of sections, the upper section of which has threads 21 thereon and a coupling device 25 at its lower end to permit the use of sections of another diameter below the same. The next section 26 has its lower end connected to the section 27 next below it by an upwardly discharging nozzle valve A which 25 may comprise two slidably connected members, a hollow perforated member 28 having an annular seat 29 above its perforated portion and a sleeve 30 having a seat 31 at its upper end to coöperate with seat 29, a hollow 30 device 32 being secured in the lower end of member 28 and coöperating with an internal annular projection 33 in the sleeve to limit the relative movement of the members of the valve. The sleeve member of the 35 nozzle is connected by a bushing 34 with the upper end of section 27. At the lower end of section 27 is arranged a nozzle valve B, which is the same as nozzle valve A, except that the device 32^a which coöperates with 40 projection 33 is not hollow and in place of bushing 34, a plug 34^a is employed and has a support 35 secured thereto to rest upon the bottom 36 of the strainer 3, which tapers 45 downwardly toward the center in order to center the air pipe within the discharge tube.

50 In operation after the installation of the apparatus in a suitable well, air under pressure from air supply 12 is admitted to the air pipe, the discharge valve 44, of course, being open. Air will now discharge upwardly from the nozzle valves A and B causing the liquid in the well to be drawn upwardly in the discharge tube and discharged through discharge 7. Should it be 55 desired to change the force of the flow from the discharge, or to entirely stop the flow, the nozzle valves A and B are operated merely by raising and lowering the upper end of the air pipe. Of course, the lower- 60 most valve B does not open until the upper

valve A has been completely opened, but as it is desirable to have the upper valve discharge the greater quantity of air, this is no objection. After the apparatus has been in operation for some time, the strainer becomes clogged as in all apparatus of this type, and to clean it, the discharge valve 44 and the air supply nozzle valves are closed, and the valves 13 and 14 are turned to admit air alternately to the well casing and the 70 discharge tube, thus producing a surging of the liquid in the well, and this surging causes the washing of the strainer. After a washing the valve 45 in a branch 46 is opened to permit the dirty liquid in the well 80 to flow off, the nozzle A and B, of course, being opened to elevate the liquid.

85 An apparatus constructed in accordance with this invention can be cleaned and also adjusted from the top of the well, thus dispensing with the dismantling of the apparatus usually required for performing these operations. The nozzle valves of which there may be any number are self cleaning and are so constructed that greater durability and greater effectiveness is secured than has been heretofore possible.

90 I claim as my invention:

1. The combination with a well casing and a liquid discharge tube, of an air supply, and means for connecting the air supply with the casing and with the discharge tube, having devices for effecting a surging of the liquid in the casing provided with discharges to the atmosphere.

95 2. The combination with a well casing and a liquid discharge tube arranged therein, of an air supply, connection between the air supply and the liquid discharge tube, connection between the air supply and the well casing and valves in said connections, having discharges to the atmosphere.

100 3. The combination with a well casing and a liquid discharge tube arranged therein, of an air supply, connection between the air supply and the liquid discharge tube, connection between the air supply and the well casing, and two way valves in said connections having discharges to the atmosphere.

110 4. The combination with a well casing and a liquid air charge tube arranged therein, of an air supply, connection between the air supply and the liquid discharge tube, connection between the air supply and the well casing, valves in said connections having discharges to the atmosphere, and means for simultaneously operating the valves to alternately supply air to the liquid discharge tube and the well casing.

120 5. The combination with a well casing and a liquid discharge tube arranged therein, of an air supply, connection between the air supply and the liquid discharge tube, connection between the air supply and the well casing, valves in said connections having discharges to the atmosphere, and means for alternately supplying air to the liquid discharge tube and the well casing.

well casing, rotary two way valves in said connections, and a shaft connected at each end to one of the valves.

6. The combination with a head formed with two chambers, one of which has a discharge, means for connecting a liquid discharge tube to one of said chambers, means for connecting a well casing to the other chamber, of an air supply, and means connecting the air supply to both chambers having discharges to the atmosphere and producing a surging action in the casing and in the liquid discharge tube.

7. The combination with a head formed with two chambers, one of which has a discharge, means for connecting a liquid discharge tube to one of said chambers, and means for connecting a well casing to the other chamber, of an air supply, and means connecting the air supply to both chambers and producing a surging action in the casing and in the liquid discharge tube, embodying two connections, two way valves in said connections, and means for simultaneously operating the valves to supply air alternately to the casing and the discharge tube.

8. The combination with a head formed with two chambers, one of which has a discharge, means for connecting a liquid discharge tube to said chamber, and means for connecting a well casing to the other chamber, of an air supply, connection between the air supply and the liquid discharge chamber, connection between the air supply and the other chamber, and valves in said connections having discharges to the atmosphere.

9. An air supply tube for liquid raising apparatus provided with an air nozzle comprising a perforated cylindrical member having a surrounding seat at one end of the perforated portion, and a member surrounding the perforated member guided on the exterior face of the latter and having a seat movable toward and from the seat on the perforated member.

10. An air supply tube for liquid raising apparatus provided with an air nozzle comprising a perforated cylindrical member having a surrounding seat thereon, at one side of the perforated portion and a member surrounding the perforated member and having a seat coöperating with the seat on said perforated member and an internal annular shoulder guided on the exterior face of the said perforated member.

11. An air supply tube for liquid raising apparatus provided with an air nozzle comprising a perforated cylindrical member having a surrounding seat thereon and a surrounding stop, and a member surrounding the perforated member and having a seat coöperating with the seat on said perforated member and an internal annular shoulder guided on the external face of said perforated member and arranged to engage the stop on the latter.

12. An air supply pipe for liquid raising apparatus provided with an air nozzle comprising a perforated member having a surrounding seat at one end of the perforated portion and a surrounding stop at the other end of said perforated portion, and a perforated member having a seat to coöperate with the seat on said perforated member and an internal flange to coöperate with the surrounding stop.

13. An air supply pipe for liquid raising apparatus provided with an air nozzle comprising a perforated member having a surrounding seat at one end and a surrounding shoulder and a projecting guide at the other end, and a member surrounding the perforated member and having a seat coöperating with the seat of the perforated member, an internal flange to coöperate with the shoulder and a portion in which the projecting guide works.
